UNITED STATES PATENT OFFICE.

WILLIAM J. HEBS AND JACOB HULTGREEN, OF CHICAGO, ILLINOIS.

MUSICAL INSTRUMENT.

Application filed July 12, 1926. Serial No. 121,798.

This invention relates in general to musical instruments such as slide trombones, but more specifically the invention relates to the valve mechanism for releasing the water or moisture which accumulates in the sliding member of the instrument.

Heretofore valves of this character have been provided but the valve being located at the base or outer end of the sliding member, access thereto has been difficult as it is necessary for the user to reach to the end of the sliding member to actuate the valve, requiring holding of the instrument in an awkward or unnatural position, to drain the moisture therefrom.

It is one of the objects of the present invention to provide an improved construction of valve and operating mechanism therefor in an instrument of this character whereby the valve may be operated from a point adjacent the hand holding portion of the slide, and which mechanism will be in a convenient position and at the same time will not present an unsightly appearance to the instrument.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a side elevation of a trombone having a valve and operating mechanism constructed in accordance with the principles of this invention applied thereto.

Figure 2 is an enlarged detailed elevation, partly in section and partly broken away of a portion of the slide member.

Figure 3 is a detached perspective view of the valve, support therefor and a portion of the operating mechanism of the valve.

Figure 4 is an enlarged detail sectional view taken on line 4-4, Figure 1.

Referring more particularly to the drawing the numeral 10 designates generally the horn portion of a trombone, 11 the slide member and 12 the mouth piece, the slide member being provided with a cross bar 13 forming a hand hold and the horn member being provided with cross bars or braces 14 by which the horn member may be grasped.

All of the above referred to parts are of the ordinary and well known construction.

The slide member 11 is provided with a discharge outlet opening 15 adjacent and to one side of the U bend 16 or outer extremity of the slide member and through which opening 15 moisture which accumulates in the instrument, during the playing thereof, is adapted to be discharged.

A valve 17 is provided to form a closure for the discharge outlet 15, and this valve 17 is connected to an arm or lever 18 pivotally mounted intermediate its ends as at 19 upon a support 20, which is attached to or forms a portion of the slide member 11. The discharge opening 15 and the valve 17 with the operating lever are disposed so that neither will be struck by any object while playing the instrument or when the instrument rests upon the floor and upon the U bend.

To the end 21 of the lever 18 is connected an operating member 22 which is constructed of any desired or suitable material, preferably wire or the like, which passes through a tubular casing 23 secured along one of the legs or portions of the slide member 11. The casing 23 terminates in an enlarged portion 24 which is connected to and preferably passes through the cross bar or brace 13 and terminates in close proximity to the brace.

An operating knob or button 25 is connected with the flexible member 22 and preferably telescopes into the enlarged portion 24. Within this portion 24 is arranged a resilient element preferably in the form of a coil spring 26, which encompasses the flexible member 22. One end of the spring abuts the base of the enlarged portion 24 and the other end abuts the extremity of the knob or button 25.

The normal tendency of the resilient element 26 is to move the lever 18 in a direction to cause the valve 17 to be seated so that it will close the discharge outlet opening 15. This will cause the knob or button 25 to be projected beyond the extremity of the enlarged portion 24 of the casing so that when the operator is holding the instrument the knob or button 25 will be in a convenient position to be engaged by one of the fingers of the hand which grips the brace or hand holding portion 13 of the slide member 11.

By depressing the knob or button 25 the lever 18 will be moved about its pivot to unseat the valve 17 and to permit the moisture to be discharged through the outlet opening 5 15.

With this improved construction it will be manifest that the valve may be readily operated at any time and in any position of the slide member and is in a convenient 19 position so that it will not necessitate the disengagement of the hand of the operator from the natural position for holding the instrument while playing.

Furthermore the valve and the operating 15 mechanism will be compactly arranged and will not be unsightly to the instrument; the tubular casing being arranged along one of the legs of the slide will not be conspicuous and will not be noticeable by a casual observer of the instrument.

While the preferred form of the invention has been herein shown and described, it is to be understood that various changes may be made in the details of construction 25 and in the combination and arrangement of the several parts, within the scope of the claims, without departing from the spirit of this invention.

What is claimed as new is:

30 1. A trombone including a slide member having a moisture discharge outlet adjacent and to one side of the U bend of the slide, a valve for controlling said outlet, a tubular casing extending along the slide member and terminating adjacent the valve, a flexible element extending through the tubular casing and connected with the valve, a cross bar on the slide forming a handle and into which

bar one end of the tubular casing projects, and an operating member connected with the flexible member adjacent the cross bar and disposed in a position to be engaged by a finger of the hand which grasps the cross bar for actuating the valve through the medium of the said flexible member. 45

2. A trombone including a slide member having a moisture discharge outlet adjacent and to one side of the U bend of the slide, a valve for controlling said outlet, a cross bar forming a handle for the slide, a tubular 50 casing extending along the slide member, one end thereof terminating adjacent the valve and the other end supported by the slide handle, a flexible element extending through the tubular casing and the slide 55 handle and connected with the valve, an operating member connected with the flexible member and disposed in a position to be engaged and depressed by a finger of the hand which grasps the slide handle for actuating the valve through the medium of the said flexible member, and a resilient element housed within said casing one end of said resilient element operating against a fixed stop and the other end operating 60 against said operating member and tending normally to close the valve and to project the operating member on the end of the flexible member beyond that side of the slide handle which is adjacent to the mouth piece. 65

In testimony whereof we have signed our names to this specification, on this 9th day of July, A. D. 1926.

WILLIAM J. HEBS.
JACOB HULTGREEN.
